[57] CLAIM

An ornamental design for a combination of high intensity lamp and built-in solid state clock, substantially as shown and described.

DESCRIPTION

FIG. 1 is a front perspective view of the combination high-intensity lamp and solid state clock showing my new design in the open position;

FIG. 2 is a rear perspective view thereof in the open position;

FIG. 3 is a rear perspective view thereof in the closed position;

FIG. 4 is a bottom plan view thereof;

FIG. 5 is a front perspective view thereof in the closed position.

The face of the solid state clock is indicated by the oblique line shading on the front surface of the base.

FIG. 1.

FIG. 2.

FIG. 3.

FIG. 4.

FIG. 5.
